CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The evenly dashed broken lines in the figures illustrate portions of the electronic device that form no part of the claimed design. The dot-dash broken lines in FIGS. 1, 2, 3, and 5 define the boundaries of the claimed design and form no part thereof.
